(57) **CLAIM**

The ornamental design for an over-mold strain relief, as shown and described.

DESCRIPTION

FIG. 1 is an isometric right-rear side perspective view of a first embodiment of an over-mold strain relief of the present invention;

FIG. 2 is a right side view thereof;

FIG. 3 is a left side view thereof;

FIG. 4 is a top view thereof;

FIG. 5 is a bottom view thereof;

FIG. 6 is a front view thereof;

FIG. 7 is a rear view thereof;

FIG. 8 is an isometric right-rear side perspective view of a second embodiment of an over-mold strain relief of the present invention;

FIG. 9 is a right side view thereof;

FIG. 10 is a left side view thereof;

FIG. 11 is a top view thereof;

FIG. 12 is a bottom view thereof;

FIG. 13 is a front view thereof; and,

FIG. 14 is a rear view thereof.

The portions shown in broken lines show unclaimed subject matter only and form no part of the claimed design.
